(57) **CLAIM**

The ornamental design for a medical transdermal patch, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a medical transdermal patch of the present invention.

FIG. 2 is a rear view of the medical transdermal patch of FIG. 1.

FIG. 3 is a top plan view of the medical transdermal patch of FIG. 1.

FIG. 4 is a bottom view of the medical transdermal patch of FIG. 1.

FIG. 5 is a right side view of the medical transdermal patch of FIG. 1.

FIG. 6 is a left side view of the medical transdermal patch of FIG. 1.

FIG. 7 is an end view of the 7-7 portion of the medical transdermal patch of FIG. 1;

FIG. 8 is an enlarged end view of the 7-7 portion of the 8-8 section of the medical transdermal patch of FIG. 1; and,

FIG. 9 is a reference view of the medical transdermal patch of FIG. 1, showing a transdermal patch partially peeled off.
